UNITED STATES PATENT OFFICE.

JOHN BEYSTRUM, OF PITTSBURG, PENNSYLVANIA.

ROTARY STEAM-ENGINE.

SPECIFICATION forming part of Letters Patent No. 311,718, dated February 3, 1885.

Application filed June 28, 1884. (No model.)

To all whom it may concern:

Be it known that I, JOHN BEYSTRUM, of Pittsburgh, in the county of Allegheny and State of Pennsylvania, have invented a new 5 and useful Improvement in Rotary Steam-Engines; and I do hereby declare the following to be a full, clear, and exact description thereof.

My invention relates to rotary steam-engines, and has special reference to certain improvements on the steam-engine shown and described in application for Letters Patent filed by me February 15, 1884, Serial No. 120,863. In that engine the cylinders were formed with eccentric inner walls, and the shaft carried a 10 cylindrical hub on each cylinder, provided with pistons sliding in seats in the hubs, the pistons fitting over rods or bars extending through the shaft and being pressed out by suitable springs. In this construction of engine it was found that it was exceedingly difficult to pack the sliding pistons within the hub, as the steam would pass down into the hub and through the main shaft around the rods to the opposite side of the piston, thus 15 decreasing the power of the engine and heating the main shaft and hub, so that they were expanded and thrown on more of a strain. It was also found that the movement of the sliding pistons required such frequent contraction and expansion of the springs that any springs 20 capable of the rapid movement required were not sufficiently strong to resist the pressure of the steam, and that stronger springs were very liable to fracture under the rapid movement. The principal object of my present invention 25 is to improve the construction of these parts of the said engine.

It consists in the combination, with a cylinder, of a shaft carrying a cylindrical hub, pistons 30 sliding in said hub and provided with pins on the outer edges, and cylinder-heads provided with grooves within which the pins travel, the grooves having their walls formed of removable wings to take the wear.

To enable others skilled in the art to make and use my invention, I will describe the same more fully, referring to the accompanying drawings, in which—

Figure 1 is a vertical longitudinal section 50 of the main cylinder. Fig. 2 is a like section of the exhaust-cylinder. Fig. 3 is a vertical cross-section of the two cylinders. Fig. 4 is

a perspective view of the cylinder-head, and Fig. 5 is a perspective view of the sliding piston.

Like letters of reference indicate like parts in each.

The rotary engine has a main or supply cylinder, A, and the exhaust-cylinder B, these cylinders being formed of rings separated by a central plate or cylinder-head, a, and of the outer cylinder-heads, c.c. Extending through the cylinders is a power-shaft, C, which is suitably packed therein, and carries the hubs E in the space of each cylinder, these hubs being cylindrical and concentric with the main shaft, while the inner walls of the cylinders are eccentric thereto, thus forming the steam-space. The engine is provided with the steam-box, f, having suitable supply-valves, d, and 60 with exhaust-valves e, these exhaust-valves leading into and communicating with the steam-space of the exhaust-cylinder B, and forming the supply-valves thereto, the exhaust-cylinder having the valves g, leading 65 into the exhaust-box g'. These parts are substantially of the construction shown and described in said application, and the faces of the drums may be packed against the cylinder-heads in substantially the manner described in said application, it not being necessary to illustrate it in the present application.

In each drum E are the seats h, these seats being formed of slots extending radially from the periphery of the hub, as shown in said application, but there being no communication between the seats or slots in the hub, and the rods on which the pistons were mounted, as shown in my former application, are dispensed with.

k are the pistons, which are made to fit the seats h neatly and correspond substantially in length to the depth of the seat h, so that they may be withdrawn into said seats. Near the end of each piston, and extending out from the edge or face thereof, are the pins l, these pins being preferably provided with the idle-rollers m, and the pins and idle-rollers being formed of hard metal, to withstand the frictional wear thereon. These pins, or pins 90 and rollers, extend out on either side of the hubs E and fit into the grooves n in the cylinder-heads, so that as the hub revolves the rollers fitting within said grooves draw the

pistons in and out of the hub. The grooves *n* are eccentric to the main shaft, and are substantially concentric to the inner walls of the cylinder, the grooves corresponding in distance 5 from the inner walls of the cylinder to the distance of the pins *l* from the end of the piston, and so holding the piston out against or substantially in contact with the walls of the cylinder, so that as the hub revolves the sliding 10 pistons mounted therein are caused to follow the walls of the eccentric cylinder.

In order to provide for the wear of the pins or idle-rollers on the walls of the grooves *n*, I have found it preferable to form the wearing-faces of the said grooves of hardened-steel rings 15 *p*, these rings being fitted within the cylinder-heads, as is illustrated in Figs. 3 and 4, and the hardened-steel faces of these rings will withstand very long wear of the guiding pins or 20 rollers within the grooves.

As it is not always possible to fit the work so perfectly that the working edge of the piston will form a steam-tight joint with the eccentric walls of the cylinder, and yet not cause 25 great friction between the pins *l* or idle-rollers *m* and the walls of the grooves *n*, I have provided the pistons with the spring packing-bars *r*, these packing-bars being formed in the shape of a T, and the T-bars fitting in corresponding T-grooves, *s*, at the working edges 30 of the piston, and extending out beyond the edges of the pistons in the center thereof, and being held out by the springs *t*, fitted in suitable seats within the pistons. As the pistons 35 are forced out by means of the eccentric grooves, the spring packing-bars are held in contact with the eccentric walls of the cylinder; but little wear or strain is thrown on the guiding pins or grooves. As the packing-bars *r* are 40 thin, the steam has but little pressure against their edges, and exerts but little force against the springs, and as the eccentric grooves cause the pistons to follow the inner walls of the cylinder, there is but little movement of the 45 springs.

The operation of the engine is substantially the same as the rotary engine described in said application. The steam passing through the supply-valves into the steam-cylinder and 50 pressing against the face of one piston forces the piston and hub round until the piston passes the exhaust-port, when the opposite piston has been carried past the supply-port, and the pressure of the live steam against it causes the

continuous rotation of the hub, while the exhaust-steam from said main cylinder is forced 55 through the valve *e* into the exhaust-cylinder *B*, and its operation in said cylinder is substantially the same as that of the live steam in the main cylinder, the steam finally passing 60 out through the valve *g* into the exhaust-box *g'*. As the steam presses against the piston *k* the guide pins or rollers fitting within the grooves *n* hold the piston out against the eccentric walls of the cylinder, and thus prevent 65 the escape of steam between said piston and the eccentric walls of the cylinder. As the steam is pressing against one side of the piston it presses the body of the piston against the opposite side of the seat *h*, and though the 70 steam may pass down into the said seat, as the body of the piston is held by the pressure thereon against the opposite wall of the said seat, it cannot pass to the opposite side of the piston. The operation is substantially the same 75 in regard to the steam-packing plates *v*.

The advantages of the engine are that it operates with less pressure than any other rotary engine known to applicant, and that though in use for some months there is no appreciable wear upon the parts. In case any of the parts should be subject to wear, the wear can only come on the guide-pins or their rollers, the side walls of the guiding-grooves, and the spring packing-bars inserted in the ends of the 85 pistons, and these parts can be replaced at but slight cost or trouble.

I am aware that rotary engines have been provided with pistons sliding in the hub thereof and provided with pins traveling within 90 guiding-grooves, and hence do not claim this broadly; but

What I claim as my invention, and desire to secure by Letters Patent, is—

In rotary engines, the combination, with a 95 cylinder, of a shaft, *C'*, a cylindrical hub secured thereon, and having the seats *h*, pistons *k*, having pins *l*, and cylinder-heads provided with the grooves *n*, having their walls formed of rings *p*, substantially for the purposes set 100 forth.

In testimony whereof I, the said JOHN BEY-STRUM, have hereunto set my hand.

JOHN BEYSTRUM.
